Patented Nov. 12, 1918.

UNITED STATES PATENT OFFICE.

FREEMAN J. BRADLEY AND MERRILL C. DIONNE, OF FOSTORIA, OHIO.

INKING-ROLL TRUCK.

1,284,867.

Specification of Letters Patent. Patented Nov. 12, 1918.

Application filed January 9, 1918. Serial No. 210,998.

To all whom it may concern:

Be it known that we, FREEMAN J. BRADLEY and MERRILL C. DIONNE, citizens of the United States, and residents of Fostoria, in 5 the county of Seneca and State of Ohio, have made certain new and useful Improvements in Inking-Roll Trucks, of which the following is a specification.

Our invention relates to improvements in 10 inking roll trucks, being more particularly in the nature of an expansible roller arranged to be fitted on each of the trunnions of an inking roll, and it consists in the constructions, combinations and arrangements 15 herein described and claimed.

An object of our invention is to provide an inking roll truck including a relatively fixed expansion rim with a relatively movable expansion cone, a plurality of expanding segments located between these members, being adapted to increase the diameter of a tire located between the cone and the rim.

Other objects and advantages will appear 25 in the following specification, reference being had to the accompanying drawing in which,

Figure 1 is a side elevation showing the improved truck applied to one of the trunnions of an inking roll.

Fig. 2 is a longitudinal section of the truck.

Fig. 3 is an elevation showing the expansion rings and segments in place on the expansion rim.

Fig. 4 is an elevation of the expansion cone.

Fig. 5 is a detail perspective view of one of the expansion segments, and

Fig. 6 is a detail view of a wrench employed in adjusting the expansion cone.

In carrying out our invention, we provide an expansion cone 1, which has a bore 2 disposed coaxially thereof. The cone 1 includes an annular shoulder 3. The body portion of the member 1 is in the shape of a frustum of a cone and provides the conical surface 4 from which the member 1 obtains its name.

The expansion cone 1 is further reduced beyond the summit of the frustum 4 and forms an annular shoulder 5. The expansion cone 1 is still further reduced beyond the annular shoulder 5, and this reduced portion is threaded as at 6, to receive the lock and jam nuts 7 and 8 respectively.

A plurality of expansion segments 9 are in contact with the conical surface of the frustum 4. The arrangement of these segments is illustrated in Fig. 3. Here it will 60 be seen that eight of the segments are employed, although obviously the number of the segments may be increased or decreased as experience may dictate.

The expansion segments are wedge-shaped 65 and the bases of the segments are substantially on the same plane with the summit of the frustum 4. An expansion rim 10 forms an abutment for the bases of the expansion segments when the expansion cone 70 1 is forced toward the expansion rim and the segments 9 are displaced radially by virtue of the wedging action of the expansion cone on the segments.

Formed in the face of the expansion rim 75 10 opposing the expansion segments, is a conical recess 11, which is so disposed that it may receive the adjacent end of the frustum 4 when the cone and the rim are drawn together. The conical recess 11 has 80 a counter-bore 12 which is adapted to receive the annular shoulder 5 of the expansion cone.

A plurality of expansion rings 13 encircle 85 the expansion segments, substantially as indicated in the drawing. These rings consist of split springs. They are made of spring metal suitable for the purpose. They form an expansible tire on the inking roll truck. The location of the split portions of the 90 rings is staggered as shown in Fig. 1, so that these split portions may not come together or line up transversely of the tire. The possibility of excessive wear and also that of the chartering of the rings is thus obviated 95

The normal diameter of the expansion rings 13 is slightly in excess of that of the annular shoulder 3 of the cone 1, and a similar shoulder 14 of the rim 10. A wrench 15 illustrated in Fig. 6, is employed in adjusting 100 the nuts 7 and 8 on the threaded end 6.

The operation of the device is as follows: The invention is in the nature of a roller having an expansible rim and this roller is ordinarily called the printing roll truck 105 in the nomenclature of the printing trade. The truck is fitted on the trunnions 16 on the ends of the inking roll 17. The truck runs on a track 18 during the movement of the inking roll over the type.

This leads to a consideration of the purpose of the expansible rim or tire of the 110

truck. Ordinarily the tire of the truck and the inking roll are of the same diameter. Varying weather conditions cause the inking roll to swell to a greater or lesser degree. Should the swollen inking roll now be run over a form having more or less vertical rulings for printing the lines on the paper, the surface of the swollen roll may be cut and seriously damaged.

10 It is now that the truck tire or rim is adjusted to compensate for the swollen inking roll. The wrench 15 is taken and applied to the lock and jam nuts 7 and 8. The nut 7 is turned to draw the expansion cone 1 toward the expansion rim 10 wherein in the expansion segments 9 are displaced radially and the tire of the truck consisting of the expansion rings 13, is expanded to the same diameter of the swollen inking 20 roll. To effect this adjustment, it is not necessary for the printer to leave the feeding position at the press. A very fine adjustment can be made with this device; a variation of a thousandth of an inch being 25 easily obtained.

As the expansion cone 1 is forced toward the rim 10, the summit of the frustum 4 moves into the conical recess 11, and the expansion segments 9 are forced radially outward by reason of the abutment of the bases of the segments on the expansion rim, and the action of the cone 4 on the wedge-shaped surfaces of the segments.

While the construction and arrangement 35 of the device is that of a generally preferred form, obviously modifications and changes may be made without departing from the spirit of the invention or the scope of the claims.

40 We claim:

1. In an inking roll truck, an expansion cone having an annular shoulder, arcuate triangular wedges superposed on the expansion cone with the bases adjacent to said shoulder, and an expansion rim engaging 45 the bases of the wedges, and having a conical recess with a counter bore, to receive the end of the cone and the annular shoulder respectively, and provide a stop for limiting the adjustment of the rim toward the cone.

2. In an inking roll truck, an expansion rim having a surface perpendicular to the axis of the inking roll to form an abutment, 55 said rim having a conical recess, an expansion cone movable toward the rim and partly entering said recess, means for draw-

ing the cone toward the rim, a plurality of wedge-shaped segments bearing on the conical surface of the cone and engaging 60 the abutment of the expansion rim, and a tire including a plurality of split rings, encircling said segments.

3. In an inking roll truck, an expansion rim having a conical recess and a counter-bore, an expansion cone including the frusto-conical body having a reduction at the summit forming an annular shoulder movable into the counter-bore, and a threaded portion projecting beyond the rim said expansion cone having a co-axial bore, a plurality of wedge-shaped expansion segments 65 engaging the frusto-conical body and contacting the expansion rim at the bases, a tire including a plurality of split rings having 70 the split portions staggeredly arranged, encircling said segments, and lock and jam nuts on the threaded portion adapted to draw the cone toward the rim to expand 75 the rings.

4. In an inking roll truck, an expansion rim having a surface perpendicular to the axis of the inking roll to form an abutment, said surface having a conical recess and a counter-bore, the periphery of the expansion rim being rabbeted at one edge to provide an annular shoulder, an expansion cone 85 consisting of a frusto-conical body having a reduction at the summit of the cone to leave an annular shoulder movable in the counter-bore, and a threaded portion projecting beyond said shoulder and through said counter-bore, the end of the expansion cone being receivable in the conical recess when the parts are screwed together, the peripheral edge of the expansion cone having a rabbeted portion to provide an annular shoulder, a plurality of wedge-shaped expansion segments 90 engaging the expansion rim abutment at the bases, the exposed portions of said segments normally lying flush with the peripheral portions of said rim and said cone beneath said annular shoulders, a tire including a plurality of split rings 95 encircling said segments and disposed in the space between said annular shoulders, said shoulders preventing the rings from slipping off, and lock and jam nuts on the threaded portion of said expansion cone to draw the cone toward the rim to expand the 100 rings.

FREEMAN J. BRADLEY.
MERRILL C. DIONNE.
